UNITED STATES PATENT OFFICE.

JOHN L. LYMAN, OF EASTHAMPTON, MASSACHUSETTS.

GARMENT-HANGER.

1,335,902.

Specification of Letters Patent.

Patented Apr. 6, 1920.

Application filed May 22, 1919. Serial No. 298,984.

To all whom it may concern:

Be it known that I, JOHN L. LYMAN, a citizen of the United States, residing at Easthampton, in the county of Hampshire and State of Massachusetts, have invented 5 certain new and useful Improvements in Garment-Hangers; and I do declare the following to be a full, clear, and exact description of the invention, such as will enable others skilled in the art to which it appertains to make and use the same.

My invention has for its object to provide an extremely simple and inexpensive, yet a highly efficient and reliable garment hanger 15 formed of a single piece of wire having a suitable amount of resiliency to grip the garment or the like by spring tension.

With the foregoing in view, the invention resides in the novel construction of the device hereinafter fully described and claimed, 20 reference being made to the accompanying drawing.

Figure 1 is a front elevation.

Fig. 2 is a side elevation.

25 Fig. 3 is a horizontal section on the plane indicated by the line 3—3 of Fig. 2.

In the manufacture of the invention, I take a single length of wire and coil the same between its ends to form a coiled 30 spring 1. One end 2 of the wire depends from the spring 1 and is coiled adjacent the latter to form an eye 3 for the reception of an attaching screw or the like 4, and the free end of the part 2 is bent to form a loop 5 and is finally bent rearwardly to provide a prong 6 which is adapted to be driven into the wall or the like to which the article is 35 attached by the fastener 4. The convolutions of the coil 1, the eye 3, and the loop 5, 40 are all preferably located in approximately the same plane as shown clearly in Fig. 2.

The other end of the wire depends from the coil 1 to form a spring arm 7 which is bent upwardly and rearwardly at 8 and then 45 forwardly at 9 to provide a gripping element adapted for coaction with the loop 5 in holding garments, towels, etc. After forming the gripping element aforesaid, the wire is wrapped around the vertical part of 50 the arm 7 and then extends forwardly to provide a preferably U-shaped hook 11 hav-

ing a rounded end 12. This hook may be used for supporting numerous articles.

By constructing the device in or approximately in the manner shown and described, 55 it may be easily and inexpensively manufactured, and less wire is required than is necessary for the construction of other similar articles.

The hanger may be used for numerous 60 purposes, but is particularly well adapted for towels, dust cloths, sweaters which are easily and often torn by the ordinary style of hooks, children's bath robes, etc. By grasping the garment or the like with both 65 hands, and stretching it tight, and then forcing it upwardly into engagement with the inclined part 8, it is easily inserted in the device and is effectively held therein by spring tension. Any other article may be 70 suspended on the hook 11 when desired.

Since probably the best results may be obtained from the details shown and described, 75 they may well be followed, but within the scope of the invention as claimed, numerous minor changes may well be made.

I claim:

A device of the class described, formed of a single length of wire coiled between its ends to form a spring, the ends of the wire 80 depending from said spring to provide front and rear arms, the rear arm being coiled between its ends to form an eye for the reception of a fastener, the lower end of said rear arm being bent to form a loop in approximately the same plane with said spring and eye and adapted to rest against the wall or the like to which the device is secured, the end of the wire after forming said loop, 85 extending rearwardly to provide a prong adapted to penetrate the wall or the like; the front arm being bent upwardly and rearwardly and then forwardly to provide a gripping element for coaction with the aforesaid loop, said forwardly extending portion being wrapped around the vertical part of said front arm and then extending forwardly to provide an article supporting hook.

In testimony whereof I have hereunto set 100 my hand.

JOHN L. LYMAN.
